UNITED STATES PATENT OFFICE.

ALBERT S. HILLS, OF HAYDENVILLE, MASSACHUSETTS.

DESIGN FOR A FAUCET-HANDLE.

SPECIFICATION forming part of **Design No. 32,496**, dated **April 10, 1900**.

Application filed January 16, 1900. Serial No. 1,694. Term of patent 14 years.

To all whom it may concern:

Be it known that I, ALBERT S. HILLS, a citizen of the United States of America, and a resident of Haydenville, in the county of 5 Hampshire and State of Massachusetts, have invented and produced a new and original Design for a Faucet-Handle, of which the following is a specification, reference being had to the accompanying drawings, forming a part 10 thereof.

In the accompanying drawings, Figure 1 is a perspective view of my design, and Fig. 2 is an end elevation of the design as seen when looking directly toward the end of one of the 15 finger-pieces.

As shown in the drawings, the leading or material feature of my design consists of the large circular central portion with the finger-

pieces elliptical in cross-section projecting therefrom and merging therewith in harmonious curves, the diameter of the central portion on a horizontal plane being greater than the diameter of the finger-pieces on the same plane. 20

Having therefore described my invention, 25 what I claim, and desire to secure by Letters Patent, is—

The design for a faucet-handle as herein shown and described.

In testimony whereof I have signed my 30 name to this application in the presence of two subscribing witnesses.

ALBERT S. HILLS.
